INVENTOR

BY Victor J. Evans

ATTORNEY

Fred W. Ely.
WITNESS:

UNITED STATES PATENT OFFICE.

BEULAH L. HENRY, OF NEW YORK, N. Y., ASSIGNOR OF ONE-FOURTH TO EDWARD B. TWOMBLY, OF SUMMIT, NEW JERSEY.

VANITY CASE.

Application filed March 29, 1923. Serial No. 628,671.

To all whom it may concern:

Be it known that I, BEULAH L. HENRY, a citizen of the United States, residing at New York, in the county of New York and 5 State of New York, have invented new and useful Improvements in Vanity Cases, of which the following is a specification.

This invention relates to vanity cases and has for its object the provision of a device 10 of this character formed of non-metallic material arranged in receptacle formation to contain rouge and powder compacts, cosmetics or various other toilet articles and constructed to permit such articles to be conveniently brought into use as desired and 15 normally contained in a sanitary manner and in a compact package.

A further object of the invention is to provide a device of this character which 20 will be ornamental, highly attractive and structurally designed to permit the device to function in a desirable manner.

With these and other objects in view, the 25 invention resides in certain novel construction and combination and arrangement of parts, the essential features of which are hereinafter fully described, are particularly pointed out in the appended claims, and are 30 illustrated in the accompanying drawing, in which:—

Figure 1 is a perspective view of the device.

Figure 2 is a vertical section therethrough.

Figure 3 is a longitudinal section through 35 one of the tubes.

Figure 4 is a perspective view showing the two receptacles opened to expose the mirror.

Figure 5 is a view similar to Figure 2 40 of the upper portion of the two receptacles showing a slightly modified form of the invention.

In carrying the invention into practice, I 45 preferably employ two receptacles 5, 5 of identical construction and arranged back to back as clearly shown in Figure 2. Each receptacle is formed of a single piece of sheet material such as thin rubber of a suitable color and brought together to provide 50 an inner wall 6 and outer wall 7, the latter having a contractible mouth 8 whose walls are associated with a strand of elastic 9 so that the mouth is normally closed. The wall 7 of each receptacle is thereby con-

structed with sufficient fullness to permit 55 the mouth 9 to be readily expanded for a purpose to be hereinafter explained.

Secured to the inner wall 6 of one receptacle 5 is a rouge compact 10 and secured in a similar manner to the corresponding wall 60 of the mating receptacle 6 is a powder compact 11. Each of these compacts is associated with a puff 12 having a manipulating portion 13 which may consist of a tassel 65 constructed of strips of rubber or any other suitable ornamental equivalent thereof which may be grasped between the fingers of the hand when it is desired to withdraw the puff from the receptacle. The contractible mouth 8 of each receptacle is such that the 70 manipulating tassel 13 is snugly embraced by the walls of the mouth and the puff retained in confinement in the receptacle against its respective compact.

At the upper part the walls of each receptacle are brought together at 14 to form a tube 15 for the reception of a lip stick, a vial of perfume or other toilet accessory. The ends of the tube portions are open as 75 shown so that the lip stick or the accessory 80 can be conveniently inserted in or removed from the tube. By forming the tube in this manner, the walls of same are elastic, and the article contained in the tube is firmly gripped by the walls to secure the article 85 against accidental loss. At the points where the walls are brought together to form the tubes 15, the receptacles are stitched or otherwise secured together to form a hinge 15^a. This permits the receptacles to be opened 90 with respect to each other. For this reason the external surface of the wall 6 of one receptacle has secured thereto a mirror 17 which may be employed when using the several cosmetics. The two receptacles may 95 be secured together by snap fastenings 18 as shown in Figure 2. At the upper end the device is provided with a suitable chain or the like 19 to permit the device to be worn from the wrist of the user.

The device constructed as described is exceedingly simple, highly useful, ornamental and attractive; is designed to hold powder and rouge compacts in sanitary arrangement and by constructing the receptacles wholly of non-metallic material, the device can be produced at a minimum cost. I am also able to make the devices in va-

rious colors that will nicely harmonize with the color of a dress and other characterizing features of the user.

In Figure 5 the receptacles 5^a are associated with a single tube 15^a. This tube is formed of a single piece of material and its ends are brought together and stitched or otherwise secured to the outer ends of the receptacles 5^a so as to provide a hinge 14^a.
10 This form is otherwise the same as the one described in the preferred embodiment.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. A receptacle formed of a single piece of material having a contractible opening, 25 the said material having portions brought together to form an open ended tube.

2. A receptacle formed of a single piece of material having an expansible opening, the said material having portions brought 30 together to form a tube for the reception of a toilet article.

3. A plurality of hingedly connected receptacles, each having an expansible opening, an applicator insertible in each receptacle through the opening thereof, and means contracting the opening to secure the applicator in an applied position.

4. A plurality of hingedly connected receptacles, each having an expansible opening, an applicator insertible in each recep-

tacle through the opening thereof, and means contracting the opening to secure the applicator in an applied position, said applicator having a manipulating portion exposed normally from said opening.

5. A vanity case comprising a receptacle formed of flexible non-metallic material and provided with an expansible opening, an applicator freely adjustable through the opening to be positioned in the receptacle, 50 a manipulating portion formed on the applicator and extending through said opening at one side of the receptacle, and a portion of said material brought together to form a tube for the reception of a toilet article.

6. A vanity case comprising two receptacles arranged back to back, a rouge compact carried by one receptacle, a powder compact carried by the other receptacle, an applicator carried by each receptacle, the two receptacles being connected together in hinge formation, and a tube associated with the receptacles for the accommodation of a lip stick, an expansible opening formed in each 65 receptacle, and a portion of each applicator projecting exteriorly of each receptacle.

7. A vanity case comprising two identical receptacles hinged together and arranged back to back, a mirror carried by one receptacle and normally disposed between the backs of both receptacles to be concealed and protected thereby, an expansible opening in each receptacle and an applicator carried by each of said receptacles and removable from 70 said receptacles without moving the same about the hinge.

In testimony whereof I hereby affix my signature.

BEULAH L. HENRY.
